(57) **CLAIM**

The ornamental design of a filter to cause sediment deposition around a storm sewer inlet, as shown and described.

DESCRIPTION

FIG. 1 is a perspective view of a filter to cause sediment deposition around a storm sewer inlet showing my new design;

FIG. 2 is a side view thereof;

FIG. 3 is a top view thereof;

FIG. 4 is a bottom view thereof; and,

FIG. 5 is a cross-sectional view taken generally on the line 5—5 of FIG. 3.

The cross-line pattern, which is partially shown for ease of illustration, represents a conventional fabric and is understood to repeat uniformly throughout the indicated area.
